SWITCH-STAND.

1,104,895.

Specification of Letters Patent. Patented July 28, 1914.

Application filed July 19, 1912. Serial No. 710,350.

To all whom it may concern:

Be it known that I, JOHN C. HOLMAN, a citizen of the United States, residing at Kansas City, in the county of Jackson and State of Missouri, have invented certain new and useful Improvements in Switch-Stands; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a switch stand, and has for its principal object to provide a stand whereby the switch points may be turned by lever mechanism having a positive action, but in which the usual tooth gears are eliminated, so that the stand cannot be rendered inoperative by rough usage or by the running of a locomotive or train through the switch.

It is also an object of the invention to provide a stand wherein the point lever and lock may be actuated by the turning of the switch points, should a locomotive or train be run through the switch and whereby the stand and connected parts are not destroyed by such action of the locomotive or train.

In accomplishing these objects, I have provided the improved details of structure hereinafter described and illustrated in the accompanying drawings, wherein:

Figure I is a perspective view of a railway switch and a switch stand constructed according to my invention. Fig. II is a side elevation of the operative parts of the stand. Fig. III is a plan view of same. Fig. IV is a perspective view of the body of the stand and the crank members, the crank head being removed for better illustration.

Referring more in detail to the parts:—1 designates a section of main track, 2 a siding and 3 the switch points for directing a train along the main track or onto the siding. Connected with the switch points is a bar 4 which extends to the side of the track and is there connected with a crank arm 5 that is fixed to the lower end of a staff 6 that is revolutely mounted in upper and lower members 7—7' of the switch stand 8. Also revolutely mounted in the members 7—7', and paralleling the staff 6, is a staff 9. The staves 6 and 9 may be ordinary sig-

nal staves, in which event they will carry one a target 10 and the other a signal lamp 11, although the invention is not limited to the combination of the switch stand with the signals, as it relates solely to the construction of the switch stand.

Fixed to each of the staves 6 and 9, is a crank arm 12 which projects forwardly from the stand and carries perpendicular posts 13, each of which has a reduced, threaded part 14 at its upper end, forming an upwardly facing shoulder 15.

Revolutely mounted on the posts 13, and seating on the crank arms 12, is a crank head 16, having downwardly projecting ears 17 provided with beveled ends 18 and separated by a U-shaped recess 19.

Rising from the center of the head 16 is a post 20 and surrounding said post is a spring 21 which is normally held under tension by a keeper-bar 22, through which the post is slidably projected, and which is fixed rigidly to the upper ends of the posts 13 by nuts, or the like, 23.

Revolutely mounted in bearing 24 on the base member 7 of the switch stand is a shaft 25, the forward end of which carries a crank arm 26 having a forwardly directed roller 27 thereon, which is adapted for engagement with either of the beveled ears of the crank head when the operating shaft is turned by the handle 28, which is attached to its rear end.

Presuming the parts to be constructed and assembled as described, and the switch points set for the main track, the handle will be in the position shown in Fig. I. Should it be desired to throw the switch for the siding, the handle is thrown to the opposite side or through a half circle, such action turning the crank arm 26 and causing the roller 27 to engage the left-hand ear of the crank head and thereby throwing the head laterally on its mounting. When the crank head is moved laterally it carries the staves 6 and 9 therewith, turning same a fourth of a revolution so as to show the proper signals by the lamp and target. When the staff 6 is turned in its bearing in the switch stand it moves the crank arm 5 so that the bar 4 is moved outwardly toward the track to move the outer switch point toward the outside rail, and the inner switch point from the inside rail, thereby opening the switch into the siding. Should a loco-

motive or train on the main track run through the switch when it is in this position, the switch points are forced laterally and turn the crank arm 5 and staff 6, such 5 action moving the crank head 16 laterally so that the ear 17 rides up the roller 27 on the crank 26 until it reaches the opposite side thereof, when it is forced downwardly by the spring 21. Inasmuch as the entire 10 movement is made by the crank head, the handle does not change its position so that the switch cannot again be thrown by the handle until the crank head is removed and readjusted. If, however, after the switch has 15 been run through from the siding, the switch points are forced back to the original position again, moving the crank head over the roller and reseating the head so that the stand may be operated in the usual manner. 20 With a stand of this construction, the destruction of the parts incident to the running through a switch, having an ordinary stand, is obviated.

Having thus described my invention, what 25 I claim is new therein and desire to secure by Letters-Patent, is:—

1. In a switch stand, the combination with a staff having means for connection with a switch point, a point lever, and a 30 head connected with the staff and adapted for actuation by the lever or for riding over the lever when actuated by the staff.

2. In a switch stand, the combination with a staff having means for connection with a 35 switch point, a point lever, a head connected with the shaft and adapted for actuation by the lever or for riding over the lever when actuated by the staff, and means for yieldingly tensioning said head toward the 40 lever.

3. In a switch stand, a revolute staff, a point lever having a crank member thereon, a mounting connected with the staff, a head 45 slidably mounted on said mounting and having ears adapted to lie on opposite sides of the crank member, and means for yieldingly tensioning said head toward the crank member.

4. A switch stand comprising a lever, 50 having a crank at one end provided with a laterally projecting member, a revolute staff, a head connected with the staff and having a bifurcated portion overlying the member on said crank whereby the head 55 may be moved by the handle member, or may be moved thereover when actuated by the staff, and a point lever connected with said staff.

5. The combination with a lever, having a 60 crank member thereon, of a revolute staff, a head connected with the staff and having

ears straddling the crank member, and a point lever connected with said staff.

6. The combination with a lever, having a crank portion, of a revolute staff, having a 65 crank arm, a head pivotally mounted on the crank arm and having downwardly projecting ears straddling the lever crank, and a point lever connected with said staff.

7. The combination with a lever having a 70 crank member, of a revolute staff having a crank arm, a post on said arm, a head pivotally mounted on said post and adapted for lateral movement when the staff is revolved, said head having spaced ears straddling the 75 crank member on the lever, and a point lever connected with said staff.

8. The combination with a lever, having a crank provided with a laterally directed roller, of a revolute staff, a head connected 80 with the staff and having downwardly projected pointed ears straddling the roller, and a point lever connected with said staff.

9. The combination with a lever having a 85 crank member thereon, of a revolute staff, a head connected with the staff and adapted for vertical movement, means for yieldingly tensioning the head toward one limit of its movement, ears on said head straddling the lever crank, and a point lever connected 90 with the staff, for the purpose set forth.

10. The combination with a lever having a crank member thereon, of a revolute staff having a crank arm, a post on said arm, a head mounted on said post and 95 adapted for pivotal and sliding movement thereon, a bar carried by said post, a post on the head slidably projected through the bar, a spring on said head post between the bar and head, ears on said head straddling 100 the lever crank, and a point lever connected with the staff.

11. The combination with a lever having a crank provided with a laterally facing roller, of a revolute staff, having a crank arm, 105 a post mounted on said arm, a head pivotally and slidably mounted on the post and having spaced, downwardly projecting, pointed ears straddling the roller on the lever crank, a bar carried by said post, a post on the head slidably projected through the bar, a spring located between the bar and head and yieldingly retaining the latter in lowered position, and a point lever connected with the staff. 110

In testimony whereof I affix my signature in presence of two witnesses.

JOHN C. HOLMAN.
